Primary Examiner—Wallace R. Burke**Assistant Examiner—H. Baynham****Attorney, Agent, or Firm—James D. Hall****[57] CLAIM**

The ornamental design for a clothes rod, as shown and described.

DESCRIPTION

FIG. 1 is a side perspective view of the clothes rod showing my new design;

FIG. 2 is a side elevational view thereof, as seen from the opposite side as shown in FIG. 1, the opposite side view being a mirror image of that shown;

FIG. 3 is a top plan view thereof;

FIG. 4 is a bottom plan view thereof;

FIG. 5 is a right end view thereof; and,

FIG. 6 is a left end view thereof.
